WINDOW AWNING

Samuel M. Brody, New York, N. Y.

Application September 9, 1952, Serial No. 308,658

8 Claims. (Cl. 160—62)

1

This invention relates to window awnings.

An object of this invention is to provide a highly improved awning of the character described, which shall be portable, and which may be compactly packed and stored away in the home when out of use, and which shall be easy to install, easy to manipulate, and light in weight.

Another object of this invention is to provide an awning of the character described, which when installed, may be manipulated or adjusted to a plurality of positions including the following:

1. Entirely closed position with the awning extending down vertically against the window.
2. Open full length position at an angle of about 45° to the window.
3. Adjustable full length position at angles less than 45° to the window.
4. For evening use, when there is no sun, the awning can be adjusted to a half awning position to allow air to come in through the window.
5. Half closed position with the awning folded in half and flat against the window.
6. Half awning in various adjusted positions less than 45°.

Still another object of this invention is to provide an improved awning of the character described having parallel arms supporting the awning sheet and also cross arms supporting the awning sheet, and which shall be provided with a double hinge to permit the lower half of the awning to be swung out and back over the upper half of the awning.

Still another object of this invention is to provide a highly improved awning of the character described, provided with cable cords to hold the awning when installing or removing the same. The cords are so arranged as to permit the awning to hang so that the awning can be manipulated into operational position.

Yet a further object of this invention is to provide supporting hooks for the awning which may be turned outwardly on their axes to keep the awning from dropping off during use.

Yet a further object of this invention is to provide a strong and durable awning of the character described which shall be relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described,

2

and of which the scope of invention will be indicated in the following claims.

In the accompanying drawings in which is shown various illustrative embodiments of this invention:

In the drawings:

Fig. 1 is a perspective view of the awning in fully extended position of use;

Fig. 2 is a transverse vertical cross sectional view through the awning shown in Fig. 1 and the window frame supporting the same;

Fig. 3 is a view similar to Fig. 2 but showing the lower half of the awning folded over the top half of the awning;

Fig. 4 is a view similar to Fig. 2 showing the awning fully extended but closed flat against the window frame;

Fig. 5 is a view similar to Fig. 4 and showing the awning dropped and hanging spaced from the window and supported by the cable cord;

Fig. 6 is a cross-sectional view taken on the line 6—6 of Fig. 2;

Fig. 7 is a cross-sectional view taken on the line 7—7 of Fig. 6;

Fig. 8 is a cross-sectional view taken on the line 8—8 of Fig. 6;

Fig. 9 is a cross-sectional view taken on the line 9—9 of Fig. 1;

Fig. 10 is a cross-sectional view taken on the line 10—10 of Fig. 1;

Fig. 11 is a cross-sectional view taken on the line 11—11 of Fig. 1;

Fig. 12 is a cross-sectional view taken on the line 12—12 of Fig. 6;

Fig. 13 is a cross-sectional view taken on the line 13—13 of Fig. 6;

Fig. 14 is a cross-sectional view taken on the line 14—14 of Fig. 13;

Fig. 15 is a cross-sectional view taken on the line 15—15 of Fig. 14;

Fig. 16 is a cross-sectional view taken on the line 16—16 of Fig. 1.

Referring now in detail to the drawing, 10 designates a window frame and 11 designates an awning embodying the invention and supported thereon.

The window frame may be of any usual construction such as a double hung window sash shown in the drawing.

It includes an outer furring strip 12 having vertical portions 13 and a top horizontal transverse portion 14. Attached to the vertical furring strips 13 are spaced upper screw eyes 15 and lower screw eyes 16. The lower screw eyes

16 are near the bottom of the window frame

and the upper screw eyes 15 are about half way up the sides of the frame. Screwed to the undersides of the top furring strip portion 14 are a pair of screw eyes 17.

The awning 11 comprises a supporting frame 20, said frame comprising a bottom horizontal bar 21 and a top horizontal bar 22 interconnected by a pair of vertical parallel rods 23. Members 21, 22 and 23 may be made of wood, plastic, metal or any other suitable material.

Attached to the ends thereof are a pair of angle shaped members 24 each having a bottom horizontal frame 25 contacting the underside of said bar, and a vertical upstanding arm 26 contacting the inside of said bar but projecting thereabove. Members 24 may be attached to the bar 21 by screws 27 as shown in the drawing.

Attached to the upper end of each arm 26 by means of a pair of lock nuts 28, is an eye bolt 29. Extending through the eye of the eye bolt 29 is a threaded shank 30 of a bolt 31 having a hook 32 at one end engaging the eye 15. Screwed onto the shank 30 is a nut 33. A lock nut 34 also screwed on each shank 30 serves to lock the nut 33 in adjusted position.

Attached to the upper bar 22 are angle-shaped members 35 having downwardly extending arms 36 extending below the bar and likewise formed with through openings to receive eye bolts 37 held in place by lock nuts 38. Extending through the eye bolts 37 are the shanks 39 of hooks 40. The hooks 40 have hook ends 41 engaging the eyes 15. Screwed to the shanks 39 are finger nuts 41 held in place by lock nuts screwed on said shanks.

It will now be observed that the frame 20 is removable from the window by unhooking the bolts 30 and 40 from the eyes 15 and 16. Said bolts 30 and 40 may be adjusted by means of the wing nuts and lock nuts thereon so as to firmly attach the frame 20 to the window frame.

For the purpose hereinafter appearing, there is screwed in the center of the bottom bar 21, a hook 45.

The rods 23 may be fixed to the horizontal bars 21 and 22 by means of transverse pins 47 or by nails or any other suitable manner.

For the purpose hereinafter appearing, there is attached to the rods 23, an aligned pair of upper cotter pins 48 and aligned pair of lower cotter pins 49. The cotter pins 48 are located below the upper horizontal bar 22 and the cotter pins 49 are located above the lower horizontal bar 21.

Slidably mounted for vertical movement on the vertical rods 23, is an intermediate cross bar 50 formed with vertical through openings 51 through which the rods 23 slidably pass. Attached to the underside of the intermediate cross bar 50, on opposite sides of the rods 23 are spring catches 53. Each spring catch 53 comprises a plate 54 attached as by screws 55 to the underside of the cross bar 50. Plate 54 is formed with apertured ears 56 carrying a transverse pivot pin 57. Pivoted thereon is a plate 58 having apertured ears 59 through which the pivot pin 57 passes. Plate 58 has an edge 60 contacting rod 23. On pivot pin 57 is a torsion spring 61 which biases the edge 60 against the rod 23. On plate 23 is a handle 62. Pressing the handle 62 upwardly the catch releases the rod 23. When both catches are open the cross bar 50 may be moved up and down. When pressure is removed from the

catches, they will automatically grip the rods 23 to hold the cross bar 50 in any vertically adjusted position.

It will be noted that the movement of the cross bar 50 is limited by the cotter pins 48 and 49.

Attached to the outer surface of the cross bar 50 are a pair of similar hinges 65 (see Fig. 11). Each hinge 65 comprises a plate 66 attached as by screws 67 to cross bar 50. Pivoted to plate 66 as at pivot pin 68 is a movable plate 69. Attached to each plate 69 as by bolts 70 is the lower end of a brace slat or bar 71. Bars 71 are parallel to one another and are interconnected by cross brace bar 72 and constitute a hinged brace. The cross brace bar 72 is interconnected to the top cross bar 22 by a pair of cords or cables 73. The ends of the cables 73 may be attached in any suitable manner to the cross brace 72 and to the cross bar 22. The length of the cables 73 is such as to be taut when the bars 71 are inclined upwardly and outwardly at an angle of about 30 degrees to the horizontal, as shown in Fig. 5 of the drawing.

Attached to the upper ends of the bar 71 as by bolts 74 are plates 75 of hinges 76. Each plate 75 has a sleeve portion 77 at its upper end carrying a cross pivot pin 78. It will be noted that the upper end of plate 75 projects above the upper end of bar 71. Hinge 76 further comprises plates 79 having sleeve portions receiving the pivot pin 78.

Attached to the plates 79 by bolts 80 or in any other suitable manner, are parallel bars 81 interconnected by intermediate reinforcing cross bars 82 and by a bottom cross bar 83. The cross bars 82 and 83 extend beyond the opposite sides of the parallel bars 81 and together constitute a base for an awning sheet as will be explained hereinafter. It will be noted that the upper ends of the bars 81 terminate short of the hinge 78.

Attached to the bars 81 are blocks 85 spaced from the hinges 76. Attached to the tops of the blocks 85 as by bolts 86 or in any other suitable manner, are the leaves 87 of hinges 88. The leaves or plates 87 have sleeves 89 at their lower ends carrying pivot pins 90. Hinged to the pivot pins are complementary leaves or plates 91 (see Fig. 10). Attached to the leaves or plates 91 as by bolts 92 or in any other suitable manner are a pair of parallel bars 93. Parallel bars 93 are in alignment with the bars 81. They are interconnected by intermediate reinforcing cross bar 94 and a top cross bar 95. The cross bars 94 and 95 extend beyond the parallel bars 93 and together constitute a second awning sheet base. The bars 82, 83, 94, 95, are of similar width.

A sheet awning 96 of any suitable flexible awning sheet material may be attached as by screws or nails 97 to the top cross bar 95, intermediate screw bars 94 and 82, and bottom cross bar 83 and hence overlies the two awning bases.

Attached to the bars 93 and 95 as by bolts 100 and 101 are angle brackets 102 having offset arms 103 formed with openings 104. Extending through each opening 104 is the shank 105, of an eye bolt 106. Each eye bolt 106 has an eye or hook 107 engaging one of the eyes 17. Screwed to the shank 105 of each eye bolt 106 is a finger nut 108 for the purpose of adjusting the position 75 of the awning.

It will now be understood that the awning is mounted on the frame 20 and is supported by the eyes 17. When the awning is in the position shown in Fig. 1, the eyes 17 may be turned outwardly into coplanar position to prevent the hooks 107 from disengaging from the eyes 17. When the cross bar 50 is moved to its topmost position contacting the upper cotter pin 48, the awning will be generally at an angle of 45°. However, the cross bar 50 may be slidably moved downwardly to any desired position thereby changing the angle of the awning. If cross bar 50 is moved all the way down into contact with the lower cotter pin 49, the awning will be fully extended, but will be flat against the window, covering the window as shown in Fig. 4 of the drawing. Attached to the lower bar 83 is a loop handle 110 which may be engaged with the hook 45 in such position to keep the awning down.

If it is desired to get more air through the window, the awning may be folded in half thus moving the awning from the position shown in Fig. 2 to the position shown in Fig. 3. In adjusting the awning from the position shown in Fig. 2 to the position shown in Fig. 3 the bars 71 are swung downwardly about hinges 65 and the bars 81 are swung in a clockwise direction about the hinges 76. During such movement members 81 are also swung in a clockwise direction about the hinges 88. Thus the bars 81 may move into overlying position with respect to the bars 93 as shown in Fig. 3 of the drawing. The awning sheet 96 is folded in half upon itself. Even in this position, the cross bar 50 may be manipulated up or down so that the half awning is adjusted to various angles.

When it is desired to remove the awning, the upper hooks 106 are disengaged from the eyes 17, and the awning is swung outwardly and downwardly so as to hang in the position shown in Fig. 5 of the drawing. In such position, the cable cords 73 are taut and support the device in said position. Then the person removing the awning may disengage the eye bolts 30 and 40 from the hooks 15 and 16, and then the entire awning may be taken off the window frame.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying

drawings is to be interpreted as illustrative and not in a limiting sense.

Having thus described my invention, I claim as new and desire to secure by Letters Patent:

- 5 1. An awning comprising a frame having top and bottom horizontal cross bars connected by vertical rods, an intermediate cross bar slidable on the vertical rods, bars hinged to the intermediate bar, bars hinged to the outer ends of the first hinged bars, bars hinged to the second hinged bars about hinges spaced from the hinge connection between the first bars and second bars, and an awning sheet attached to the second and third bars.
- 10 2. A device according to claim 1, and flexible cords connecting the first hinged bars with the top cross-bar.
- 15 3. A device according to claim 2, and means to limit the sliding movement of the intermediate cross-bar on said vertical rods.
- 20 4. A device according to claim 1 and means to attach said awning frame to a window frame.
- 25 5. An awning construction, comprising a supporting frame, means on the frame to disengageably attach the same to a window frame, a member slidable vertically on said supporting frame, a brace hinged to said vertically slidable member, an awning sheet base hinged to said brace, a second awning base hinged to the first awning base about an axis spaced from and parallel to the hinged connection between the first awning base and the brace, and an awning sheet attached to the first and second awning bases.
- 30 6. A device according to claim 5, and means to detachably attach the outer end of the second awning base to the window frame, and means to limit the vertical movement of said vertically slidable member.
- 35 7. A device according to claim 5, and means to retain said vertically slidable member in various vertical positions.
- 40 8. A device according to claim 7, and flexible means interconnecting the brace with the supporting frame to limit the movement of said brace about said vertically slidable member.

SAMUEL M. BRODY.
